UNITED STATES PATENT OFFICE.

LOUIS J. CRECELIUS, OF ST. LOUIS, MISSOURI.

RAILWAY TRACK-DRILL.

SPECIFICATION forming part of Letters Patent No. 375,670, dated December 27, 1887.

Application filed May 26, 1887. Serial No. 239,384. (No model.)

To all whom it may concern:

Be it known that I, LOUIS J. CRECELIUS, of St. Louis, Missouri, have made a new and useful Improvement in Railway Track-Drills, of 5 which the following is a full, clear, and exact description.

The present improvement, in part, is designed more especially to take the place of a portion of the track-drill described in a pending application of mine for Letters Patent therefor, filed May 5, 1887, and numbered serially 10 237,258. Another part—namely, the means for supporting the drill-brace—is wholly auxiliary thereto. I desire, however, not to be restricted 15 to the drill referred to, the improvement now under consideration being applicable to other forms of drills.

The features of the improvement are the automatic positive drill-feed independent of any 20 spring tension and requiring no adjustment, and the adjustable brace-support.

The preferable form of the improvement is shown in the annexed drawings, making part 25 of this specification.

Figure 1 is a view showing the ratchet mechanism, the drill-frame, and a portion of the drill-brace in horizontal section. Fig. 2 is a section on the line 2 2 of Fig. 1. The view is looking toward the drill-brace; and Fig. 3 30 is a view in perspective of the feed-regulating disk. Fig. 4 is a view in perspective of the feed-nut. Fig. 5 is a view in perspective from the inner side of that part of the drill-frame which contains the bearing in which the feed-dog works. Fig. 6 is a view in perspective of 35 the feed-dog bearing, the view being from the outer side of the drill-frame. Fig. 7 is a view in perspective of the feed-dog. Fig. 8 is a view in perspective of the thumb-nut. Fig. 40 9 is a view in perspective of the adjustable brace-leg. Fig. 10 is a view in perspective of another adjustable brace-leg; and Fig. 11 is a view in perspective showing that part of the brace to which the drill-frame is attached, and 45 illustrating the application of the adjustable legs.

The same letters of reference denote the same parts.

The improvement is illustrated in connection with the railway track-drill referred to.

Only such parts of the construction are in-

cluded in the drawings as are needed for an understanding of the present improvement.

a^2 represents the main bar of the drill-brace. B, Fig. 1, represents the rail being drilled. 55 C represents the frame containing the mechanism for operating the drill D.

The drill-frame is adapted to turn and to be slipped laterally upon the main bar a^2 by means of the sleeve e, and the sleeve can be clamped 60 at the desired point of adjustment by means of the set-screw e'.

The ratchet E is provided with, or made in one piece with, the tubular spindle E', which is journaled in the frame C at e. The ratchet-lever F is journaled upon the spindle E' at e'. The squared or feathered screw for feeding the drill is shown at G. It is journaled in the frame C at e', and its outer end is adapted to bear indirectly or directly against the drill, all substantially as in the original construction, saving as modified by the present improved mechanism, and as follows:

H, Figs. 1, 3, represents what I term the "feed-regulating cam." It has a central 75 square perforation, h, to enable it to be fitted onto the screw or follower G, so as to be carried around with the screw in its rotation; and it resembles a circular washer, saving that it is notched at h^1 and one side h^2 , and preferably both sides, $h^2 h^3$, of the notch are beveled, substantially as shown in Fig. 3.

I represents a feed-nut. It has a threaded central perforation, i, Fig. 4, to enable it to be passed onto the screw, or follower and to 85 engage therewith, so that when held stationary it shall operate to feed the screw when the last-named part is rotated. The feed-nut is also provided with, or constructed to form, a ratchet, i', whose notches i^2 in width conform 90 to the notch h^1 in the regulating-cam. One side, i^3 , of the notches i^2 is beveled; but the opposite side, i^4 , of the notches is constructed to form a shoulder. The feed-nut is arranged upon the screw G against or near the regulating-cam, and the cam and feed-nut in the present instance are arranged between the ratchet-spindle and the part e' of the drill-frame, substantially as shown in Fig. 1.

J represents a dog of the shape shown more 100 distinctly in Fig. 7. It is held and adapted to be moved longitudinally in a bearing, j, Figs.

1, 5, 7, in the drill-frame. The bearing is opposite the regulating-cam and feed-nut, and the inner end, j' , of the dog is wide enough and is suitably shaped to engage simultaneously in 5 the cam-notch, and also in that one of the feed-nut ratchet-notches which for the time being is abreast the cam-notch. The spring j^2 , encircling the stem j^3 of the dog, acts, whenever the cam-notch is opposite the dog, to move the dog 10 into the cam-notch and also the coincident feed-nut notch. The dog-stem passes outward through the bearing in the drill-frame, and at its outer end is provided with a thumb-lever, K. This last-named part is provided with the 15 beveled lugs k , Figs. 1, 2, 8, and the outer end of the bearing j at j^4 , Figs. 1, 6, is notched, the sides j^5 of the notch being beveled. The thumb-lever lugs are adapted to engage in the notch j^4 , as seen in Fig. 2, and when thus engaged 20 the dog, by the action of the spring j^2 , is moved far enough inward into the bearing j to enable it to engage in the cam-notch as described; but by rotating the thumb-lever upon the dog-stem into a position at right angles to 25 that of Fig. 2—namely, into the position of Fig. 1—the lugs k are jumped out of the bearing-notch j^4 , and the dog is now drawn so far outward in the bearing j as to prevent it from engaging with the cam-notch.

30 The operation of this improvement as thus far described is as follows: The ratchet, ratchet-spindle, and drill are operated in the usual manner, and the cam is carried around with the screw. At every revolution the cam-notch 35 is presented to the dog, which, saving when the thumb-lever has been adjusted, as described, to hold the dog without the field of the cam, then drops into the cam-notch, and also into that one of the feed-nut notches which is at the 40 side of the cam-notch. In Fig. 2 the dog is shown in engagement with the feed-nut notch. The cam continues to rotate with the screw; but the feed-nut is now held stationary by reason of the dog encountering the shoulder. The 45 screw now feeds, and it continues to feed until the cam has been carried around to bring the dog to the farther side of the cam-notch, and until the dog has been lifted up the beveled side of the cam-notch sufficiently for the dog 50 to clear the shoulder in the feed-nut. The feeding of the screw or follower G and drill then ceases until the cam is carried around again, and its notch is again presented to the dog. The cam-notch can be varied in width, 55 as indicated by the broken line, Fig. 3. The cam can also have more than one notch. I prefer in the present instance a single notch, and also to have the cam-notch, the feed-nut notches in number and width, and the pitch of the 60 screw relatively conform, so that for every revolution of the screw and cam the screw shall be fed a certain distance, as thereby the operator is enabled not only to obtain an automatic positive feed, but also to make the

amount of the feed conform to the revolution 65 of the screw.

Another feature of the improved drill is the support for the brace. In addition to the fixed leg, which is connected with or made part of the sleeve c , I employ an adjustable leg, L, 70 Figs. 9, 11. It is in effect a sleeve adapted to be slipped upon the main bar at one side of the sleeve c , and it is provided with a projection, l , by which means the drill-brace can be upheld upon a support—such as a tie—which 75 is at one side of the drill-frame. The leg can not only be slipped upon the main bar, but also can be rotated thereon to suit the shape or exact position of the support beneath, and be held in any desired position with the set-screw l' . An additional means—such as the 80 chair M, Figs. 10, 11—can also be used to uphold the brace. The chair is shaped to receive the main bar, and it has a projection, m , to raise the brace sufficiently from the support 85 beneath. The chair is permanently attached to the drill, say by means of the chain m' . The chair can thus, within the limit of the chain, be placed more or less at the side of the 90 drill-frame. Both the leg L and the chair M can be used together to advantage in placing the drill, and as they are both permanently attached to the drill they are not liable to be lost.

I claim—
1. In combination, a drilling-tool held in a 95 rotating ratchet, a screw or follower arranged in rear of said tool and operated by the ratchet to advance said tool longitudinally, a nut on said screw for controlling the movement thereof, and automatic means for causing intermittent movement of the screw longitudinally, substantially as described.

2. In combination, a drilling-tool carried and operated by a ratchet, an independent 105 screw in rear of the tool and adapted, in connection with a controlling-nut, to be operated automatically by the movement of the ratchet to advance the drilling-tool longitudinally, substantially as described.

3. In combination, the drilling-tool carried and rotated by the ratchet, the feed-screw in rear thereof having longitudinal movement, a controlling-nut on said screw having rotary movement, and means for holding said nut stationary, whereby the rotary movement of the ratchet will operate to advance the screw, substantially as described.

4. The combination of the drill-brace, the leg L, and the chair M, said leg being made to slip and to turn upon the main bar, and said chair being attached to the brace by means of the chain, as described.

Witness my hand.

LOUIS J. CRECELIUS.
